Primary Examiner—A. Hugo Word**Assistant Examiner—Doris V. Coles****Attorney, Agent, or Firm—Marger, Johnson, McCollom & Stolowitz****[57] CLAIM**

The ornamental design for a fishing lure, as shown and described.

DESCRIPTION

FIG. 1 is a perspective view of the fishing lure showing my new design;

FIG. 2 is a right side elevational view, the left side being a mirror image thereof;

FIG. 3 is a front elevational view thereof;

FIG. 4 is a rear elevational view thereof;

FIG. 5 is a top plan view thereof; and,

FIG. 6 is a bottom plan view thereof.

The broken line showing of a hook in FIG. 2 is for illustrative purposes only and forms no part of the claimed design.
